(57) **CLAIM**

The design for a seat for use in row seating, as shown and described.

DESCRIPTION

FIG. 1 is a perspective view from in front and one side of a seat for use in row seating, showing my new design;

FIG. 2 is a front elevational view thereof;

FIG. 3 is a top plan view thereof;

FIG. 4 is a side elevational view thereof, the corresponding view from the other side being a mirror image; and,

FIG. 5 is a rear elevational view thereof.
